UNITED STATES PATENT OFFICE.

ISAAC STROUSE, OF NEW HAVEN, CONNECTICUT.

DESIGN FOR A CORSET.

SPECIFICATION forming part of Design No. 12,600, dated December 13, 1881.

Application filed November 9, 1881. Term of patent 7 years.

To all whom it may concern:

Be it known that I, ISAAC STROUSE, of New Haven, in the county of New Haven and State of Connecticut, have invented a new Design 5 for Corsets; and I do hereby declare the following, when taken in connection with the accompanying drawing and the letters of reference marked thereon, to be a full, clear, and exact description of the same, and which said drawing constitutes part of this specification, and represents in the figure a front view.

This invention relates to a design for ornamenting the breast-sections of a corset; and it consists in the ornamentation as shown in the 15 accompanying illustration, and hereinafter described.

In the illustration, A represents the front or clasp section, and B the hip-section, the intermediate section, C, being the breast-section, 20 extending from top to bottom. At its upper end the gores *a b c* are shaped, starting from a point at their lower end and running upward to about the center of the breast, thence contracting toward the top. The surface of these 25 gores is ornamented by a series of cords or ribs.

The body of the section B is divided at the upper end, forming tongues *d e*, running up respectively between the gores *a b* and *b c*. 30 Centrally down these tongues *d e* ribs or cords

are run, continuing down the surface of the section respectively to its rear and front edge, leaving a plain space below the central gore and between the ribs, which may be ornamented by embroidery or otherwise, the essential feature of the design being the gores curved from their point at the bottom, expanding to the center of the breast, then contracting toward the top, combined with the vertical ribs running from between the gores down to the 40 lower end of the section. 35

I claim—

The herein-described design for corset, consisting of the breast-section having the three gores *a b c* at the top, starting from a point at 45 their lower end, expanding by a curved line to about the center of the breast, thence contracting to the top, with the tongues *d e* of the section extending up between the gores, the said gores ornamented by the series of ribs, 50 and the section ornamented by ribs or cords starting from the top between the sections and running downward on the face of the section to the bottom, as shown in the accompanying illustration.

ISAAC STROUSE.
